UNITED STATES PATENT OFFICE

148,450

DESIGN FOR A SMOKING STAND OR THE LIKE

Henry T. Warner, Chicago, Ill.

Application July 12, 1946, Serial No. 131,527

Term of patent 14 years

(Cl. D85—2)

To all whom it may concern:

Be it known that I, Henry T. Warner, a citizen of the United States, residing at Chicago, in the county of Cook and State of Illinois, have invented a new, original, and ornamental Design for a Smoking Stand or the Like, of which the following is a specification, reference being had to the accompanying drawing, forming a part thereof.

The figure on the drawing is a perspective view of a smoking stand, showing my new design.

I claim:

The ornamental design for a smoking stand or the like, as shown.

HENRY T. WARNER.
